BOBBIN SORTING APPARATUS

Louis M. Cotchett, Hingham, Mass., assignor to
 Foster Machine Company, Westfield, Mass., a
 corporation of Massachusetts

Application July 11, 1944, Serial No. 544,451

16 Claims. (Cl. 209—72)

1

This invention relates to bobbin sorting apparatus of the kind used for selectively sorting bobbins or like supports for yarn or thread which have some residual yarn or like threads thereon from those which are completely free from such material, whereby to salvage for future use the yarn or the like remaining on any such bobbins.

More specifically, the present invention relates to such bobbin sorting apparatus as defined above which may be used in conjunction with winding machines and particularly those winding machines which are adapted to automatically doff the supply bobbins as they are used up. With such automatic doffing, it frequently occurs that a doffed bobbin will not have had all its yarn exhausted therefrom and the present invention provides means to segregate those bobbins with residual yarn from those which are clean of such yarn.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate embodiments of the invention, and together with the description, serve to explain the principles of the invention.

It is the object of the present invention to provide a new and improved sorting apparatus of the kind generally and more specifically referred to hereinbefore.

It is a further object of the invention, to provide a new and improved sorting apparatus which will positively identify and segregate bobbins or the like thread or yarn carriers which have some residual yarn thereon from those which have not.

Of the drawings:

Figure 1 is an end elevation of one embodiment of the sorting apparatus according to the invention, having parts cut away to expose certain operating elements of the apparatus;

Figure 2 is a plan view of the apparatus of Figure 1;

Figure 3 is a detailed view of operating elements of the apparatus when in selective sorting position with respect to a bobbin having some residual threads or yarn thereon;

Figure 4 is a detailed view of operating elements of the apparatus when in initial selective

2

sorting position with respect to a bobbin having no residual threads or yarn thereon;

Figure 5 is a cross-section on the lines 5—5 of Figure 3; and,

Figure 6 is a detailed view, similar to Figure 4, with the operating elements of the apparatus in a further selective sorting position.

Generally, sorting apparatus of the present invention comprises means for bringing the bobbins as they are discarded from the winding or other bobbin using machine to a sorting station where the individual bobbins are explored for any remaining yarn or threads thereon, after which the bobbins are projected or dispatched toward one or another locality depending upon whether or not yarn or threads were discovered thereon.

The means for bringing the bobbins to the sorting station may comprise a conveyor belt which, in the case of utilization with a winding machine with automatic doffing of used bobbins, may extend throughout the length of the winding machine and in a position to receive the bobbins as they are doffed. Alternatively, if manual doffing is to be utilized, the conveyor belt may extend along the machine with which it is being used at a convenient locality to receive the used bobbins as they are removed by hand.

Preferably, at one end of the belt or like means for bringing the bobbins to the sorting station, there is arranged a chute for conveying the bobbins to the means for exploring their surfaces for residual threads.

As each bobbin drops to the lower part of the chute it is picked up and carried forwardly toward the exploring means by conveyor means, for example, a continuous chain conveyor and, at a predetermined point in the travel of each bobbin, feelers with gripping faces are slid across the surface of the bobbin.

If there is any thread left upon the bobbin, the gripping faces of the feelers are engaged thereby so that the feelers share the further upward movements of the bobbin as it travels on the chain conveyor, and at a predetermined point in that upward travel the feelers cause means to be projected into the path of one end of the bobbin to slew it out of line and permit it to be obliquely projected into a suitable location or a receptacle, for bobbins with threads thereon, for salvage.

Should there be no thread on the body of the bobbin, the feelers slide on the smooth face thereof and permit the bobbin at its other end to contact means to slew it out of line in the other direction, whereby it will be obliquely projected

into another and different location or receptacle, for bobbins bare of threads.

The belt conveyor and chain conveyor may be driven from the same source of power which may be a separate prime mover such as an electric motor so that the sorting apparatus may be an autonomous unit or alternatively, the conveyors may be suitably driven from the winding or like machine to which the sorting apparatus may be attached, or with which the sorting apparatus may be associated.

It will be understood that the foregoing general description and the following detailed description as well are exemplary and explanatory of the invention but are not restrictive thereof.

Referring now to the accompanying drawings, and particularly Figures 1 and 2, a moving belt 10 is provided for receiving the discarded or doffed bobbins 11 and for carrying these forward to a sorting station for examination for any residual thread thereon.

Belt 10 moves in the direction of arrow A (Figure 2) and is preferably an endless belt driven by a driving chain 12 and a driving chain sprocket 13 mounted on a shaft 14 which shaft is in turn driven by bevel gears 15 and 16 from a main driving shaft 17 driven for instance from a prime mover (not shown). Chain drive 12 drives a chain sprocket 18 fixedly mounted on the shaft 19 which carries the belt pulley 20 about which belt 10 passes and by which the belt 10 is frictionally driven. A suitable take up belt pulley similar to pulley 20 will be provided at the other end of belt 10, but is not shown. Shaft 19 is suitably mounted in bearings 21 in the main supporting frame of the apparatus formed partly by members 22 and 23, and the shaft 14 is rotatably supported by the frame member 22 near its lower end by a bearing 24.

Supported by frame members 22 and 23, are upstanding side guides 25 and 26 running parallel with the belt 10 and extending thereabove a sufficient amount to prevent any of the bobbins similar to 11 moving along with the belt 10 from being discharged therefrom.

Located at the forward extremity of the run of belt 10 is a chute 28 which is adapted to receive the bobbins similar to 11 as they come toward the sorting station, the chute receiving the bobbins and passing them to the sorting means.

The bobbins are deflected and directed into chute 28 by an angularly extending deflector 30 which may be formed with guide 25 and conveniently, the guide 25 and deflector 30 may be formed in one piece and attached to side wall 31 of the chute. The other side wall 32 of the chute may equally be joined to guide 26.

As shown in Figure 1, the chute 28 slopes sharply downward, whereby the bobbin 11 will fall by gravity down the lower sloping wall 33 and into a pocket 34 in the lowermost part of the chute which is shaped to suit the general contour of the bobbin, now shown in this position, in full lines at 35 in Figure 1 and in dotted lines in Figure 2.

The front wall 36 of the chute 28 is also shaped generally to the contour of the bobbin 35 at the bottom of the chute, and the chute 28, formed of the side walls 31 and 32, front wall 36 and lower wall 33 is supported by frame members 37 and 38 in the form of channels extending vertically parallel to the frame members 22 and 23 and attached thereto by frame members 39 to form the main frame of the apparatus. Main drive shaft 17, driven from a suitable source of

power such as a prime mover (not shown) extends between channels 37 and 38 and is journaled therewithin and carries at either of its ends a chain sprocket 40 around which a pair of continuous chains 41 pass, the arrows B and C in Figure 1 showing the direction of moving of the chains.

At the upper end of the channels 37 and 38 there is rotatably mounted across the channels a shaft 42 upon which is fixed at each end a sprocket 43 similar to sprockets 40, for receiving the chains 41, bearings 45 supporting the shaft within the channels.

Attached to the links of chains 41 at preselected points are a plurality of hangers 46, comprising thin plates formed at their forwardly presented face to a hook-shape adapted to pick up the successive bobbins received in the lowermost portion 34 of the chute 28 in the cradle formed by the hook-shaped parts, the hangers 46 being arranged on the two parallel moving chains 41 in associated pairs, each pair being adapted to engage and pick up bodily a bobbin, such as 35, near its ends and carry the picked up bobbin in the cradle parts of the hangers upwardly from the chute 28.

The lower wall 33 and part of the front wall 36 of the chute 28 are cut away, as at 47, to permit the hangers 46 to pass through and into the lowermost part 34 of the chute 28 and gather up the bobbin 35 lying there.

Thus, the series of pairs of hangers 46 continuously move upwardly into engaging position with respect to the bobbins as they assume the position of bobbin 35 and progressively move the successive bobbins delivered down chute 28 from belt 10 upwardly, to a sorting station to be hereinafter described, the bobbins each being moved from the position occupied by bobbin 11 to the position occupied by bobbin 35, thence to be cradled and picked up by a pair of hangers 46 to occupy the position of the bobbin 48 and thereafter to be carried up to position occupied by the bobbin 49, these positions being progressively shown in Figures 1 and 3.

Means are provided to permit exploring of the surface of the bobbins during their upward movement and preferably as they approach the top of the run of sprockets 43 at about the position of bobbin 49 in Figures 1 and 3, to ascertain whether there is any remaining thread thereon which can be salvaged, and means are also provided for separating bare bobbins without such remaining thread from those with such remaining thread.

To this end, a pair of feelers 50 are provided each comprising a curved plate having the underside projecting downwardly toward bobbins supported on hangers 46 as these come upwards from position 48 to position 49, the said underside being roughened, serrated or grooved to form extending teeth 51 as clearly shown in Figures 3, 4, 5 and 6.

Each of the feelers 50 terminate at one end in an upwardly extending lug 52 which is pivotally attached to an operating lever, the one feeler 50 being pivoted at 53 to a lever 54 extending from a pivotal connection 55 with channel 38 toward channel 37, and the other feeler 50 being pivoted at 56 to a lever 57, extending from a pivotal connection 58 with channel 37, toward channel 38.

As better shown in Figure 2, pivotal connections 55 and 58 each comprise a rod 59 suitably

journalled in the leaves of each channel 37 or 38, as at 60.

In order to give stability to the levers 54 and 57 their ends journalled to the channels are formed substantially as L-shaped sections 61, 62.

In accordance with the present invention it is desired that the levers 54 and 57 shall share movements about their respective pivots, and to this end the two levers are linked together intermediate their ends, one of the levers having a slot in which the pivoting means ride, to permit equal movements of the levers about their pivot points 55, 58 under upward urging caused by a thrust exerted on either of feelers 50, and to this end, the two levers 54, 57 brought together at a median portion by offsetting each lever as at 64, 65 to provide a pair of arms 66, 67 lying in close parallel relationship in the horizontal position of levers 54, 57 shown in Figures 4 and 6.

A pivot pin 68 having a head 69 is fixedly mounted in one arm, such as 67, and passes through arm 66 which is slotted at 72 to permit sliding of the pin 68 therein when the levers 54, 57 are swung upwardly about their pivots 58, 55, a retaining nut 70 being threaded on the free end of the pivot pin 68.

Referring now specifically to Figure 3, 4, 5 and 6, the respective stages of operation with respect to detecting existing thread on the bobbin and subsequent sorting of bobbins from bobbins free of such thread will now be made clear.

In Figure 4, a bobbin 75 is shown approaching the top of the upward run of chains 41 carrying hangers 46 in one pair of which hangers 76 the bobbin 75 is supported. Bobbin 75 is clear of any residual yarn or thread and thus its surface, which may be wood, cardboard, plastic material or the like, is smooth. As it moves upwardly, depending feelers 50 are contacted, the serrations or teeth 51 thereof running freely over the surface of the bobbin under its continued rise. Due to the smooth uninterrupted surface contacted by the teeth 51 there will be no tendency for them to engage or stop in their sliding over the surface, this result being obtained by the feelers 50 swinging around their pivots 53 and 56.

Accordingly, with no part of the surface of bobbin 75 capable of catching and holding teeth 51 from sliding therewith, the arms 66, 67 forming part of levers 54, 57 will remain horizontal being held in that position by stops 77, 78 fixed to the channels 37, 38, the downward weight of the various parts of levers 54, 57 acting to normally retain this horizontal position against the stops, as hereinafter brought out.

As the bobbin 75 continues to rise to the position in Figures 5 and 6, the feelers 50 will pivot about their carrying levers 54, 57, moving around the pivotal attachments 53, 56 until the bobbin 75 assumes the uppermost position on top of sprockets 43, this being indicated in Figures 5 and 6. Further movements of the bobbin 75 over the top of sprockets 43 toward the downward reach of the chains 41 results in one end of the bobbin 75 striking an extension on arm 66, this extension being in the form of a depending lug 79 acting as a pusher. The resulting contact of one end of the bobbin 75 with pusher lug 79 will cause the bobbin to be tipped from contact with the cradle of one of its hook shaped hangers 76, so that as the downward reach of the chains 41 is started the bobbin 75 will be obliquely thrown or allowed to drop to one definite side where it can be deposited in a suitable receptacle (not shown)

for bobbins free of any residual yarn or thread or collected in any other obvious manner.

Specifically, as viewed in Figure 6, the right hand end of bobbin 75 will be restrained by pusher lug 79, with which it is shown in contact, thus detaching the left hand end of the bobbin 75 from its left hand hanger 76, and as the hangers start to invert their position on the downward reach, the bobbin 75 will be thrown down obliquely and to the right of Figure 6, to be collected in any desired manner.

Figure 3 clearly illustrates the action of the apparatus when a bobbin, shown as the bobbin 49, has some thread remaining thereon as at 80.

As the bobbin 49 rises, the teeth 51 of feelers 50 first contact the surface of the bobbin and then slide along until they come into engagement with the yarn on the bobbin. Teeth 51 of either or both the feelers 50 depending on location and extent of the residual yarn, become fast therein, and, as seen in Figure 3, the left hand feeler 50 has its teeth 51 locked in the yarn 80 on the left hand end of the bobbin 49.

Upon further rising of the bobbin 49 the left hand feeler 50 will raise lever 57 on which it is mounted upwardly, and due to the interlinking by pivot pin 68 of levers 54, 57, both of these will simultaneously be progressively raised up by the urge of the upward climb of bobbin 49. As they reach the maximum position, which is as illustrated in Figure 3, and which is determined by the size and placement of sprockets 43, the pusher lug 79 on arm 66 will have been moved out of operative position, but a similar pusher lug 82 attached to the other arm 67 which forms part of the lever 57 has been placed in position for operation on the other end of the bobbin 49 whereby, when the levers 54, 57 are raised, due to the presence of thread such as 80, on a bobbin, pusher lug 82 will act on the left hand end of the bobbin to throw obliquely the bobbin to the left, as it is carried over the top of the sprockets 43, to be collected, as by a suitable receptacle (not shown).

The relative positioning and shaping of pusher lugs 79 and 82 are clearly shown in Figures 4 and 6, lug 82 depending below lug 79 so that in the position of Figure 4, which pertains when the bobbin is free of yarn, as is bobbin 75, the left end of the bobbin clears over the pusher lug 82 but strikes pusher lug 79, while in Figure 3, it will clearly be seen that the pusher lug 79 has been raised out of operative position with the simultaneous raising of pusher lug 82 into operative position, the positions of Figure 3 pertaining when yarn is present on the bobbin, as shown with bobbin 49.

The weight of the feelers 50, which are made large enough to adequately explore the surface of a bobbin, together with the weight of pusher lugs 79 and 82 forming extensions of the levers 57 and 54 beyond their common pivot 68, cause the levers 54, 57 to assume the normal position shown in Figure 4, namely, disposed against the restraining stops 77, 78, in a substantially horizontal position.

Hangers 46 may be attached to chains 41 in any suitable manner, and are preferably removable to permit of adjustment of sizes to provide a variability of use of the sorting apparatus adapting it to different sizes of bobbins or like discarded yarn supply carriers.

According to this invention, there is thus provided a shorting apparatus adapted to receive, explore and sort bobbins containing a remaining portion of yarn from bobbins free of yarn, where-

by the yarn remaining can be salvaged. Obviously, the sorting device can receive upon its belt 10 the discarded bobbins by hand or can be so associated with a winding or similar machine as to receive bobbins when automatically doffed.

The main drive shaft 17 may be driven from any source of power, such as an electric motor (not shown) mounted within frame channel members 37, 38, whereby the sorting apparatus of this invention may form an autonomous unit, or the main drive shaft 17 may be suitably driven from a driving shaft on the winding or like machine with which the sorting apparatus is to be used, to which it may be attached or into which it may be incorporated.

The invention in its broader aspects is not limited to the specific mechanisms shown and described but departures may be made therefrom within the scope of the accompanying claims without departing from the principles of the invention and without sacrificing its chief advantages.

What is claimed is:

1. A bobbin sorting apparatus of the kind described and including in combination conveying means for directing the bobbins to be sorted toward a sorting station, detecting means engageable with a bobbin and moveable longitudinally thereof for progressively exploring the surface of each bobbin at said sorting station, and selective means rendered operative by said detector means for directing bobbins in one direction when said bobbins contain any residual yarn, and in another direction when said bobbins are bare of residual yarn.

2. A bobbin sorting apparatus of the kind described and including in combination conveying means for directing the bobbins to be sorted toward a sorting station, detecting means engageable with a bobbin and moveable longitudinally thereof for progressively exploring the surface of each bobbin at said sorting station, and obstructing means operatively connected with said detecting means adapted to be placed in the path of travel of a bobbin when said detecting means detect the presence of threads on said bobbin, to alter the direction of travel of said bobbin.

3. A bobbin sorting apparatus of the kind described comprising in combination conveying means for carrying a bobbin through a predetermined path of travel, exploring means engageable with the surface of a bobbin and moveable axially thereof for searching the surface of the bobbin during said travel to detect existence of residual yarn thereon, and directing means for changing the path of travel of said bobbin actuated by said exploring means only upon detection of yarn thereby upon said bobbin.

4. A bobbin sorting apparatus of the kind described comprising in combination conveying means for carrying a bobbin through a predetermined path of travel, exploring means for searching the surface of the bobbin during said travel to detect existence of residual yarn thereon, and a pair of directing means each for changing the path of travel of said bobbin in a different oblique direction, one of said directing means being normally in the predetermined conveyed path of travel of said bobbin for changing the path of travel of said bobbin if devoid of residual yarn and being removed from said predetermined conveyed path of travel by said exploring means only upon detection of yarn of said bobbin.

5. A bobbin sorting apparatus of the kind described comprising in combination conveying

means for carrying a bobbin through a predetermined path of travel, exploring means for searching the surface of the bobbin during said travel to detect existence of residual yarn thereon, and a pair of directing means each for changing the path of travel of said bobbin in a different oblique direction, one of said directing means being normally in the predetermined conveyed path of travel of said bobbin for changing the path of travel of said bobbin if devoid of residual yarn and being removed from said predetermined conveyed path of travel by said exploring means only upon detection of yarn of said bobbin, the other of said directing means being normally out of the predetermined conveyed path of travel of said bobbin, and being brought into said predetermined conveyed path of travel with the removal therefrom of the first direction means.

6. A bobbin sorting apparatus of the kind described comprising in combination conveying means for carrying a bobbin through a predetermined path of travel, exploring means for searching the surface of the bobbin during said travel to detect existence of residual yarn thereon and a pair of directing means each for changing the path of travel of said bobbin in a different oblique direction, one of said directing means being normally in the predetermined conveyed path of travel of said bobbin for changing the path of travel of said bobbin if devoid of residual yarn and being removed from said predetermined conveyed path of travel by said exploring means only upon detection of yarn of said bobbin, the other of said directing means being normally out of the predetermined conveyed path of travel of said bobbin, and being brought into said predetermined conveyed path of travel simultaneously with the removal therefrom of the first direction means by said exploring means upon detection of yarn of said bobbin.

7. A bobbin sorting apparatus of the kind described and including in combination conveying means for directing the bobbins to be sorted toward a sorting station, a second conveying means for delivering said bobbins successively to said sorting station, feeling means for progressively exploring the surface of each bobbin during the delivery of each successive bobbin to the sorting station, and selective means rendered operative by said feeling means for obstructing one end or the other end of every successive bobbin for slewling the bobbins out of their normal path of movement and directing bobbins in one direction when said bobbins contain any residual yarn, and in another direction when said bobbins are bare of residual yarn.

8. A bobbin sorting apparatus of the kind described comprising in combination a belt for delivering the bobbins to a sorting station, a lifting conveyor for carrying each bobbin successively toward said sorting station, a pair of feelers at said sorting station adapted to explore the surface of each bobbin during its upward movements on said conveyor, a pusher normally in the path of the conveyor adapted to engage one end of each bobbin thereon, a second pusher normally out of the path of the conveyor adapted to be moved into a position to engage the other end of each bobbin, and means controlled by the movements of said feelers in contact with the surface of a bobbin for projecting one or the other of said pushers into the path of movement of the bobbin on the conveyor, to slew it to one side or the other and cause the bobbin to be obliquely deposited from the conveyor in one direction or another.

9. A bobbin sorting apparatus of the kind described comprising in combination a lifting conveyor for carrying each bobbin successively toward a sorting station, feelers at said sorting station adapted to explore the surface of each bobbin, a pusher normally in the path of the conveyor adapted to engage one end of each bobbin thereon, a second pusher normally out of the path of the conveyor adapted to be moved into a position to engage the other end of each bobbin, and means controlled by the movements of said feelers in contact with the surface of a bobbin for projecting one or the other of said pushers into the path of movement of the bobbin on the conveyor, to slew it to one side or the other and cause the bobbin to be obliquely deposited from the conveyor in one direction or another.

10. A bobbin sorting apparatus of the kind described comprising in combination a lifting conveyor for carrying each bobbin successively toward said sorting station, a pair of feelers at said sorting station adapted to explore the surface of each bobbin during its upward movements on said conveyor, a pusher normally in the path of the conveyor adapted to engage one end of each bobbin thereon, and means controlled by a feeler for permitting retention of said pusher in normal position when a bobbin has no residual yarn thereon, to slew one end of said bobbin to one side and cause it to be obliquely deposited from the conveyor.

11. A bobbin sorting apparatus of the kind described comprising in combination a lifting conveyor for carrying each bobbin successively toward said sorting station, a pair of feelers at said sorting station adapted to explore the surface of each bobbin during its upward movements on said conveyor, a pusher normally out of the path of the conveyor, and means controlled by a feeler for projecting said pusher into the path of movement of said conveyor and into engaging position with respect to an end of a bobbin when residual yarn is detected thereon, to slew the end of the bobbin to one side and cause the bobbin to be obliquely deposited from the conveyor.

12. A bobbin sorting apparatus of the kind described comprising in combination a belt for delivering the bobbins to a sorting station, a lifting conveyor for carrying each bobbin successively toward said sorting station, a pair of feelers at said sorting station adapted to explore the surface of each bobbin during its upward movements on said conveyor, a pusher normally in the path of the conveyor adapted to engage one end of each bobbin thereon, a second pusher normally out of the path of the conveyor adapted to be moved into a position to engage the other end of each bobbin, and means controlled by the movements of said feelers in contact with the surface of a bobbin for projecting one or the other of said pushers into the path of movement of the bobbin on the conveyor, to slew it to one side or the other and cause the bobbin to be obliquely deposited from the conveyor in one direction or another, said means comprising yarn engaging teeth on said feelers, a pivoted arm for pivotally supporting each feeler, said arms being linked together intermediate their length and carrying said pushers at their extremities.

13. A bobbin sorting apparatus of the kind described comprising in combination a lifting conveyor for carrying each bobbin successively toward a sorting station, feelers at said sorting station adapted to explore the surface of each bobbin, a pusher normally in the path of the con-

veyor adapted to engage one end of each bobbin thereon, a second pusher normally out of the path of the conveyor adapted to be moved into a position to engage the other end of each bobbin, and means controlled by the movements of said feelers in contact with the surface of a bobbin for projecting one or the other of said pushers into the path of movement of the bobbin on the conveyor, to slew it to one side or the other and cause the bobbin to be obliquely deposited from the conveyor in one direction or another, said means comprising yarn engaging teeth on said feelers, a pivoted arm for pivotally supporting each feeler, said arms being linked together intermediate their length and carrying said pushers at their extremities.

14. A bobbin sorting apparatus of the kind described comprising in combination a lifting conveyor for carrying each bobbin successively toward said sorting station, a pair of feelers at said sorting station adapted to explore the surface of each bobbin during its upward movements on said conveyor, a pusher normally in the path of the conveyor adapted to engage one end of each bobbin thereon, and means controlled by a feeler for permitting retention of said pusher in normal position when a bobbin has no residual yarn thereon, to slew one end of said bobbin to one side and cause it to be obliquely deposited from the conveyor, said means including a pivoted arm to which said feeler is pivoted said arm carrying said pusher at its extremity, and serrated yarn engaging teeth on said feeler, adapted to slide upon a bobbin which is bare of residual yarn.

15. A bobbin sorting apparatus of the kind described comprising in combination a lifting conveyor for carrying each bobbin successively toward said sorting station, a pair of feelers at said sorting station adapted to explore the surface of each bobbin during its upward movements on said conveyor, a pusher normally out of the path of the conveyor, and means controlled by a feeler for projecting said pusher into the path of movement of said conveyor and into engaging position with respect to an end of a bobbin when residual yarn is detected thereon, to slew the end of the bobbin to one side and cause the bobbin to be obliquely deposited from the conveyor, said means including a pivoted arm to which said feeler is pivoted, said arm carrying said pusher at its extremity, and serrated yarn engaging teeth on said feeler adapted to grip said yarn on said bobbin and cause uplifting of said arm to place said pusher in the path of movement of one end of said bobbin.

16. A bobbin sorting apparatus of the kind described comprising in combination a belt for delivering the bobbins to a pick up station, a chute, down which the bobbins fall, a lifting conveyor for successively picking up the bobbins and carrying them to a sorting station, a pair of feelers each pivotally mounted on an arm and having a serrated yarn engaging surface presented toward the uprising bobbins each of said arms being pivotally attached at one of their ends and linked intermediate their length to each other, a lug projecting from the free end of one arm into the normal path of one end of a bobbin, and a lug projecting below the first lug and normally below the normal path of movement of the other end of the bobbin, whereby upon presence of yarn upon a bobbin the teeth of the feelers will engage and raise up said arms so that said second lug is in the path of movement of said other end of the bobbin, to obliquely dislodge the bobbin in

11

one direction from the conveyor, and upon absence of yarn on a bobbin the feelers will ride smoothly on the bobbin face and the first named lug will engage the one end of the bobbin to obliquely dislodge the bobbin in another direction from the conveyor.
